SPOON HOLDER

Madolyn Hassler, Stephenville, Tex.

Application September 2, 1949, Serial No. 4,838

Term of patent 14 years

(Cl. D44—10)

To all whom it may concern:

Be it known that I, Madolyn Hassler, a citizen of the United States of America, residing at Stephenville, in the county of Erath and State of Texas, have invented a new, original, and ornamental Design for a Spoon Holder, of which the following is a specification, reference being had to the accompanying drawing, forming part thereof.

Figures 3 and 4 are, respectively, front and rear elevational views thereof.

I claim:

The ornamental design for a spoon holder, substantially as shown.

MADOLYN HASSSLER.
